DESIGN FOR A TABLE

Arthur L. Slee, San Francisco, Calif.

Application March 3, 1933, Serial No. 47,392

Term of patent 14 years

To all whom it may concern:

Be it known that I, ARTHUR L. SLEE, a citizen of the United States of America, residing in the city and county of San Francisco, State of California, have invented a new, original, and ornamental Design for a Table, or Similar Article, of which the following is a specification, reference being had to the accompanying drawing, forming part thereof.

The figure is a perspective view of a table, showing my new design.

The nature of my design, as fully represented

in the accompanying drawing, comprises a table, or similar article, in which the legs are formed of sections, each section having an even thickness throughout, and successive sections gradually diminishing in thickness to give a tapered appearance and effect to said legs, with an annular skirt or flange at the junctions of said sections.

I claim:

The ornamental design for a table, or similar article, as shown and described.

ARTHUR L. SLEE.
